FREDRICH KLINKERMAN, OF AURORA, INDIANA.

Letters Patent No. 87,176, dated February 23, 1869.

IMPROVED TOLL-COLLECTOR FOR GRIST-MILLS.

The Schedule referred to in these Letters Patent and making part of the same.

To whom it may concern:

Be it known that I, FREDRICH KLINKERMAN, of Aurora, Dearborn county, Indiana, have invented a new and useful Toll-Collector for Grist-Mills; and I do hereby declare the following to be a full, clear, and exact description thereof, reference being had to the accompanying drawings, making part of this specification.

My invention relates to an automatic device for enabling the owner of a grist-mill to separate and direct into its proper receptacle such proportion of the grain as falls to his share.

Figure 1 is an axial section of a toll-collector embodying my invention.

Figure 2 is a top view of the same, with a portion of the hopper broken away.

A may represent a portion of the floor of the mill, having a circular aperture, *a*, to receive and hold the principal spout, *B*, which spout is cylindrical at its upper part, and surmounted by a flange, *C*, that rests upon an annular seat or ring, *D*, which encircles the aperture *a*, and is fastened to the floor by means of screws *E*, or otherwise.

The said spout, at its lower portion, is sloped downward and outward, as shown, and has, in its sloping bottom, *b*, and concentric with the aforesaid cylindrical portion, a neck or toll-duct, *F*, which, extending somewhat above the said bottom, *b*, affords a seat for my "divider," *G*, which consists of a wheel, whose spokes, *H*, correspond in number with the fraction or portion of grain to be taken for "toll."

The hub *I* of this wheel is flared, and hollowed downward, and has opening into it a duct, *J*, whose upper end corresponds with the space between two consecutive spokes, so as to enclose exactly one-eighth, or other fraction, as the case may be, of the entire area of the wheel.

The upper end of the wheel receives a central stud or spindle, *k*, which projects downward from a bar, *K*, that extends athwart a hopper, *L*, whose legs, *l*, rest

partly upon the ring *D*, to which said hopper is firmly secured by bolts *M*, and partly upon the flange *O* of the spout *B*, which they hold securely in place, while permitting of the adjustment or partial rotation of said spout about its axis, so as to discharge in any desired direction.

Appended to the lower end of the "toll-duct" *F*, so as to be capable of adjustment about the common axis, is my toll-spout, *N*.

Projections *O* and *O'*, from the spouts *B* and *N* respectively, may afford means of attachment of a rod, cord, or other appliance for adjusting the said spouts, and for holding them to any desired position.

Thus these spouts can be so adjusted as to discharge into the same or any different bins desired.

When set to discharge into different bins, perfectly proportional distribution of the customer's and miller's shares of grain is secured, by causing the divider to slowly revolve, by means of a belt, *P*, or otherwise.

Q and *R* are orifices, for lubricating the bearings of the divider.

An inferior modification of my toll-collector may have the spouts *B* and *N* fixed instead of adjustable.

I claim herein as new, and of my invention—

1. The rotary divider *G*, formed, arranged, and operating, in connection with a duct, *J*, substantially as set forth.

2. The combination of rotary divider *G* with centrally-discharging duct *J*, and spout *B* with centrally-discharging neck *F*.

3. The combination of the main spout and toll-spout, when either or both are adjustable about a common axis, substantially as herein described.

In testimony of which invention, I hereunto set my hand.

FREDRICH KLINKERMAN.
